VACUUM PUMP

John M. Dougherty, St. Louis, Mo.

Application June 26, 1935, Serial No. 28,465

10 Claims. (Cl. 103—252)

This invention relates to vacuum pump devices such as are used in low pressure steam heating plants wherein steam is admitted to a tank and condensed therein to draw water from the system, and the admission of a fresh supply of steam forces the water into the boiler or the circulating system.

A device of the same general type is illustrated and described in Patent No. 1,999,687, issued to me April 30, 1935, and some elements embodied in the structure of the present invention are described in said patent.

The prior art structures referred to utilize a float in the condensing tank for controlling the admittance of steam thereto intermittently.

The object of the present invention is to increase the efficiency of the device by making the same more quickly responsive to changes in the water level in the condensing tank. Briefly, this general object is attained by controlling the steam inlet valve with a thermostat exposed alternately to steam direct from the boiler and to water direct from the return system, which is usually 30 to 40° cooler than the steam. The thermostat is operatively connected to a steam valve, and preferably an air valve also, to control the passage of fluids to and from the tank.

Other detail objects of the invention and the means for attaining the same will be apparent from the following description, reference being had to the accompanying drawing in which—

Figure 1 is a vertical section through the condensing tank and some of the apparatus associated therewith, other portions of the apparatus being indicated in elevation and some electrical equipment being shown diagrammatically.

Figure 2 is a corresponding section through some of the parts shown in Figure 1 but showing the same in a different operating position.

The condenser tank is indicated at 1 and is provided with a series of air flues 2 extending lengthwise through the same. A blower 3 at one end of the tank is operated by a motor 4 to draw air through the flues and discharge the same through a conduit 5 to a portion of the building to be heated. The steam pipe 6 leads from the boiler and has branches 6a and 6b. The return pipe 7 leads from the heating system direct to the boiler water supply pipe 8. A lateral 9 leads from pipe 7 to the upper portion of tank 1 to admit water to the tank. A discharge pipe 10 leads from the lower portion of the tank back to the boiler supply line 8. Check valves 11, 12, 13, and 14 prevent the flow of water through

these pipes in directions opposite to the arrows adjacent the valves.

All of the above mentioned parts are well known and in themselves do not constitute the present invention.

A thermostatic device 15 includes an element 16, extending substantially the full depth of the tank, and parts associated therewith arranged to raise and lower the plunger 17 which is connected to a lever 18 pivoted at 19 and mounting a mercury switch 20. A spring 21 tends to hold lever 18 in the position shown in Figure 1 in which switch 20 is in position to open the electric circuit controlled thereby. A steam inlet valve 22 controls the passage of steam from branch 6a through pipe 23 to the interior of the tank. A spring 24 tends to raise the valve disc 25 from its seat and a solenoid 26, when energized, closes the valve against the tension of spring 24.

Preferably the steam inlet and the thermostatic element 16 are located near opposite ends of the tank.

A pipe 27 leads from the interior of the tank to an air relief valve 28, the disc 29 of which is normally raised from its seat by a spring 30. A solenoid 31, when energized, moves disc 29 against its seat, overcoming the tension of spring 30. Solenoids 26 and 31 are energized through a single circuit which is closed by switch 20 when the latter and the parts associated therewith are in the position shown in Figure 2.

A supplementary or emergency control for the structure is provided and includes a float 32 pivoted at 33 and having a lost motion connection to a bell crank 34 connected by a link 35 to a lever 36 operating a valve 37 connecting steam pipe branch 6b with the interior of the tank.

Operation.—Assuming the system to be cold and tank 1 substantially filled with air and the parts are in the position shown in Figure 1, the first steam generated by the boiler will be led directly through pipe 6a and valve 22 into the tank at the end opposite the air relief pipe 27. The steam will force a substantial portion of the air out through valve 28 and will heat thermostatic element 16 until element 17 moves upwardly, shifting mercury switch 20 and closing the circuit which energizes solenoids 26 and 31, whereupon valves 22 and 28 close and the admittance of steam to the tank is interrupted. The cool air surrounding the tank and passing through flues 2 condenses the steam, creating a partial vacuum in the tank and drawing water into the tank through pipe 9. Since the end of pipe 9 is

near the top of the tank, any cool water discharged therefrom will have the maximum opportunity of contacting with any steam remaining in the tank and will promptly condense the same.

As the temperature in the tank decreases, particularly if sufficient water is admitted to contact with element 16, the thermostat operates to shift switch 20 in the opposite direction, opening the circuit and permitting springs 24 and 30 to open valves 22 and 28 admitting an additional quantity of steam which heats the thermostatic element 16 and the cycle of operations is repeated so long as the system is in operation. After a substantial amount of water has been drawn into the tank, subsequent admission of steam results in the discharge of water through valve 14 and pipe 10 to the boiler return pipe 8.

Any tendency of water to escape, under steam pressure, through air relief pipe 27 and valve 28 will result in the immediate closure of the valve passage by a float 38 which normally rests on projections at the base of the valve and is not affected by the passage of air through the valve and has no function except as just described.

If the water should rush into the tank faster than the thermostat controlled mechanism can function to open steam valve 22, float 32 will be raised and steam valve 37 will be opened and the pressure thereby set up in the tank will terminate the inflow of water.

The current of air induced by blower 3 not only serves to provide a space heater but also accelerates the condensing action occurring in the tank. The circuit for motor 4 is controlled by the hand operated switch S only and the action of the blower is continuous and not intermittent as is the device controlled by switch 20.

The structure described is illustrative only and the details of the structure and assembly may be substantially varied without departing from the spirit of the invention. Obviously suitable linkages could be provided between the thermostat and valves 22 and 30 to operate the valves, or the valves could be motorized and controlled by electric switch similar to that shown. The emergency float controlled steam inlet may be unnecessary in some installations and can be omitted. I contemplate the exclusive use of these and all other modifications of the invention coming within the scope of my claims.

I claim:

1. In a structure of the class described, a condensing tank, means for admitting water to said tank and for discharging water therefrom, a valve for admitting steam to said tank, a thermostat constructed and arranged for contact by the air, steam, and water in said tank, and an electromagnet and spring mechanism controlled by said thermostat to open said valve when said thermostat is cooled and to close said valve when said thermostat is heated, a float, operable by the water in said tank, and means actuated by said float when the water in said tank reaches an abnormally high level, to admit steam to said tank independently of said thermostat.

2. In a structure of the class described, a condensing tank, means for admitting water to said tank and for discharging water therefrom, a valve for admitting steam to said tank, a thermostat device including an element arranged for successive contacts by relatively small quantities of steam and water in said tank and electromagnet and spring means controlled by said device and operatively connected to said valve to respective-

ly close and open the latter when exposed to steam and water in said tank, a float, operable by the water in said tank, and means actuated by said float when the water in said tank reaches an abnormally high level, to admit steam to said tank independently of said thermostat. 5

3. In a structure of the class described, a condensing tank, means for admitting water to said tank and for discharging water therefrom, a valve for admitting steam to said tank, a thermostat including an element in the lower portion of said tank, and electromagnet and spring means controlled by said thermostat operatively connected to said valve to open the same when said element is exposed to water or cool air in said tank and to close said valve when said element is exposed to steam in said tank, a float, operable by the water in said tank, and means actuated by said float when the water in said tank reaches an abnormally high level, to admit steam 20 to said tank independently of said thermostat.

4. In a structure of the class described, a condensing tank, means for admitting water to said tank and for discharging water therefrom, a valve for admitting steam to said tank, a thermostat device having an element in said tank exposed to steam present in said tank and to water present in the lower portion of said tank, electromagnet means controlled by said device when said element is cooled by water admitted 30 to said tank, to open said valve, and means controlled by said device, when said element is heated by steam admitted by said valve, to close said valve, a float, operable by the water in said tank, and means actuated by said float when the water 35 in said tank reaches an abnormally high level, to admit steam to said tank independently of said thermostat.

5. In a structure of the class described, a condensing tank, means for admitting water to said 40 tank and for discharging water therefrom, a valve for admitting steam to said tank, a thermostat extending into said tank and having an element shifted to different positions when said thermostat is heated and cooled, an electric circuit having a switch opened and closed by shifting of said element, and an electromagnet in said circuit for controlling said valve, a float, operable by the water in said tank, and means actuated by said float when the water in said tank 45 reaches an abnormally high level, to admit steam to said tank independently of said thermostat.

6. In a structure of the class described, a condensing tank, means for admitting water to said tank and for discharging water therefrom, a 55 valve for admitting steam to said tank, a thermostat extending into said tank and having an element shifted to different positions when said thermostat is heated and cooled, an electric circuit having a switch closed by said element when heated, an electromagnet energized by said circuit when closed to open said valve, and a spring for opening said valve when said element is heated to open said switch, a float, operable by the water in said tank, and means actuated by said 60 float when the water in said tank reaches an abnormally high level, to admit steam to said tank independently of said thermostat.

7. In a structure of the class described, a condensing tank, means for admitting water to said 70 tank and for discharging water therefrom, a valve for admitting steam to said tank, a valve for venting air from said tank, a thermostat extending into said tank, and means controlled by said thermostat, when cooled by direct contact 75

with water in said tank, to open both of said valves and when heated by steam in said tank to close said valves.

5 8. A structure as described in claim 7 which also includes a float member constructed and positioned to close said air venting valve upon the flow of water into the same.

10 9. In a structure of the class described, a condensing tank, means for admitting water to said tank and for discharging water therefrom, a valve for admitting steam to said tank, a valve for venting air from said tank, a thermostat ex-

tending into said tank and having an element shifted to different positions when said element is heated and cooled, an electric circuit having a switch connected to said element, and electrically controlled devices in said circuit for actuating said valves to admit steam to said tank and to vent air from said tank concurrently.

5 10. A structure as described in claim 9 which also includes a float member constructed and positioned to close said air venting valve upon the flow of water into the same.
